Specialty Corporation, Detroit, Mich., a corpo-
ration of Michigan

Application July 19, 1940, Serial No. 346,410
In Great Britain July 26, 1939

2 Claims. (Cl. 122—392)

This invention relates to fluid heater cleaners of the kind comprising a movable blower element adapted to be projected for operation from a retracted position and after operation to be withdrawn to that position, one object being the provision of a fluid heater cleaner of such construction as to facilitate maintenance. A further object is the provision of a fluid heater cleaner with a form of pressure part which makes for ease in manufacture and is suitable for use with high pressure cleaning fluid. A further object of the invention is the provision of automatic control means for the pressure fluid, so arranged that adjustments of the angle or angles over which blowing is effected may readily be made.

According to the present invention a fluid heater cleaner of the kind specified includes a pressure part formed with an aperture of sufficient diameter to permit withdrawal of the movable blower element which extends therethrough and with a valve chamber containing a valve for controlling the supply of pressure fluid to the aperture and thence to the blower element and provided with a closure member arranged to permit direct access to the valve seating. Preferably the said part is a forging.

In one embodiment of the invention the pressure part is in the form of a forging of rectangular shape and the valve is arranged for operation by a piston under the control of a pilot or relay valve arranged automatically to be operated in dependence upon the position of the blower element.

The invention will now be described by way of example with reference to the accompanying drawings, in which:

Figure 1 shows a longitudinal sectional elevation of a fluid heater cleaner of the kind specified embodying the improvements according to the invention;

Figure 2 is a plan view of Figure 1;

Figure 3 is a sectional view to a larger scale on the line III—III of Figure 1;

Figures 4 and 5 are views on a larger scale than Figure 1 showing alternative forms of cam for giving different blowing angles;

Figure 6 is a sectional view on the line VI—VI of Figure 4, and

Figure 7 is a view of the washer 86 looking from the left of Figure 1.

Referring to Figures 1 and 2 of the drawings, 1 denotes the blower tube which is formed in one with a solid spindle 2 and is fitted with a blower nozzle 3, these parts together forming

the blower element. The blower element may be projected from the retracted position shown by longitudinal movement relatively to the pressure part 4 through the aperture 5 in which the element extends.

The pressure part 4 is a rectangular forging and is formed with a cylinder 6 for a piston 7 the longitudinal axis of which is transverse to that of the blower element and a relay valve 8 is disposed in a cover plate 9 to the pressure part 4. Thus an underlying valve chamber 10 is disposed in a cover plate 9 to the pressure part 4. and the cylinder 6 extend in a vertical direction upwardly from the aperture 5 in the pressure part 4 which is surmounted by the cover-plate 9 closing the cylinder 6 and secured in position by studs and nuts 11. The actual surfaces of contact between cover plate 9 and pressure part 4 are provided by the end of an annular projection 12 and the bottom of an annular recess 13 formed in the upper surface of the pressure part 4 around the cylinder 6.

A fixed valve seat 14 is disposed at the bottom of the valve chamber 10 and is screwed into the opening 15 between the valve chamber and aperture 5 and is directly accessible and may be inspected and attended to or replaced by removing the cover plate 9 and the piston 7 with associated parts including movable valve lid 16 and a biasing spring 17 disposed within the piston 7 around a central sleeve 18 and bolt 19. As shown, the valve lid 16 is held to bolt 19 by a flanged collar 20 screwed into the valve lid and clamping the latter against the bolt head 21. A nut 22 screwed onto the bolt 19 serves to clamp the end of piston 7 through which the bolt passes, between the sleeve 18 and shoulder 23 on the bolt and acts as a stop to limit opening of the valve by engaging the inside of the cover plate 9 which is suitably recessed at 24 to receive and position one end of the spring 17, the other end of which bears against the end of the piston.

The relay valve 8 includes a spindle 25 the axis of which is disposed in a plane parallel to the axis of the blower element and a cam 26 on the blower element is arranged to transmit movement to the spindle 25 through a tappet 27 transverse to the blower element and a lever 28 intermediate the spindle and tappet. In the arrangement shown the spindle 25 is parallel to the axis of the blower element, the relay valve 8 being arranged as a removable unit secured in a recess 29 in the cover plate 9, which recess is in communication with the cylinder 6 through a port 30.

55 The spindle 25 of the relay valve slides through

a sleeve 34, the inner end of which is clamped against a shoulder 35 in the recess 29 by a threaded ferrule 36 screwed into the recess and bearing against the annular shoulder 37 on the sleeve. The inner portion of the sleeve 34 is formed with ports 38 and the adjacent portion of the spindle 25 is of reduced diameter so that when the movable valve face 39 formed near the inner end of the spindle is moved from the valve seat 40 on the sleeve, fluid is able to pass into the annular space 41, and through the ports 38 into the annular space 42 and thence to a duct 43 in the cover plate. The spindle 25 is biased to the closed position by a spring which acts between seatings in the ferrule 36 and a head 45 screwed onto the spindle and the lever 38 operates the relay valve by pressing against the head 45. The lever 38 is pivoted to, and the tappet 27 is arranged to slide in a bracket 31 secured to the pressure part 4 by studs 100 and the length of the tappet 27 is adjustable, whilst a pin and slot arrangement 32 prevents rotation of the tappet 27 and thus maintains proper orientation of a roller 33 at the lower end of the tappet 27 in relation to the cam 26.

The relay valve 8 is arranged to exhaust pressure fluid acting on the upper side of piston 7 to the inner side of a wall 46 of the fluid heater. Thus a tube 47 is arranged to conduct the fluid from the duct 43 in cover plate 9 to a duct 48 leading to the interior of a wall box 49 clamped by screws 98 to the front side of the pressure part 4, the tube being readily disconnectable from the cover plate 9 by means of the joint 50.

According to the connection required, the one side or the other side of the forged pressure part is bored and provided with studs and nuts 51 for the connection of a pressure fluid pipe 52 for supplying pressure fluid, generally steam, to the valve chamber 10 and a flanged aperture 53 is provided on the wall box 49 adjacent to the pressure part for the admission of cooling fluid, such as air, to the interior of the wall box. Suitably the pressure fluid pipe 52 is provided with a stop valve (not shown) whereby the pressure part 4 may be isolated to permit of attention to the valves or piston.

The cam 26 which is external to the pressure part 4 is readily removable. Thus as shown more particularly in Figure 3 the cam is divided into two parts 54 and 55 which together embrace the part 56 of the spindle 2 of reduced diameter and are removably secured thereto. Conveniently the cam is secured to the spindle 2 by a screw 57 which passes through the bore 58 in cam part 54 and the diametrical bore 59 in the part 56 of the spindle 2 and screws into the cam part 55 thereby clamping the cam parts 54 and 55 against the spindle 2. It follows that by removing the screw 57 the parts of the cam may be removed from the blower element. It will be seen that the part of the screw 57 adjacent its head is of enlarged diameter and that one end of bore 59 and the bore 58 in cam part 54 are of corresponding size. This ensures that the position of the cam parts 54 and 55 shall not accidentally be interchanged, an error which it is important to guard against when the two parts are not symmetrical. The cam shown is arranged to give a blowing angle of nearly 360 degrees, but the two parts 54 and 55 are formed with inclines 60 and 61 respectively, referred to hereinafter. The arrangement is such that the roller 33 when the head of screw 57 is adjacent thereto engages the cam surface to one side of the slot 101 of cam part 54 which accommodates the screw head.

The blower element slides through joints requiring no lubrication. Thus the element slides with a somewhat loose fit through a sleeve 62 at the front and an adjustable packing 63 at the rear of the pressure part 4. The adjustable graphited packing 63 is provided in the pressure part 4 itself between neck ring 64 and gland 65 whilst the sleeve 62 is provided at the forward end of a cylindrical extension 66 screwed and welded to the forging and projecting within the wall box 49.

The nozzle 3 which discharges at an angle to the longitudinal axis of the blower element and the angular position of which relatively to the blower tube 1 may readily be adjusted is screwed into the blower tube and locked in position by a lock nut 67 whilst the solid spindle 2 is formed towards its extremity with a screw thread 68 hereinafter referred to, adjacent the part 56 of the spindle to which the cam 26 is secured. The blower tube 1 at its rear end is formed with ports 69 which always lie in the pressure fluid chamber 70, which is formed by the parts of the aperture 5 and extension 66 between the sleeve 62 and neck ring 64 and which is arranged to receive pressure fluid from the valve chamber 10 through the opening 15. Thus when the valve lid 16 is lifted, pressure fluid flows from the valve chamber 10 into the chamber 70 and thence through the ports 69 and blower tube 1 to the nozzle 3.

The blower element may be turned by a concentric gear wheel 71 through a key 72 and keyway 73 and rotation of the blower element causes longitudinal movement thereof through co-operation between the screw thread 68 and a fixed nut 74 rigidly secured to a bracket 75, the limbs 76 of which are clamped by studs 99 to the pressure part 4. As shown more particularly by Figure 1 there is sufficient space between the limbs 76 to allow ready access to the cam 26. The gear wheel 71 and an intermeshing wheel 77 connected with a driving shaft 78 are contained in a split housing 79 mounted upon the end of bracket 75 upon which a cylindrical extension 80 of the housing fits and is clamped by a screw 81. As shown the gear wheel 71 is positioned longitudinally by the surfaces 82 and 83 respectively of parts of the housing and the end of bracket 75 and is provided with bearing surfaces 84 and 85 on the bracket 75 and housing 79 respectively.

Suitable stops are arranged directly to oppose further rotation of the blower element in its end position. Thus clamped to the rear end of the blower element is a washer 86 formed on its periphery with shoulders 87 and 88 which abut against stops 89 and 90 formed on the interior of a housing 91 which is clamped to the gear casing 79 and which serves to enclose the end of the blower element. Instead of providing both stops 89 and 90 within the housing 91, one only 89, may be formed therein at the rear end thereof, the other, 90, being located within the outer end of the gear case 79.

Figures 4 and 6 show a cam for giving a blowing angle smaller than that given by the cam of Figure 1. In this case the cam consists of a single part arranged to be clamped to the blower element by a screw passing through the part 56 of the element and screwing into the threaded hole 92 of the cam. A projection 93 on the cam by engaging the recess 94 in the part 56 of the blower element assists in positioning the cam. Inclines 95 and 96 on the cam are provided at the ends of the cam surface corresponding to the blowing period.

The cam shown in Figure 5 is similar to that

shown in Figures 4 and 6, corresponding parts being similarly numbered, but is arranged for a smaller blowing angle.

In the operation of the cleaner described, when the shaft 18 is rotated in the forward direction, the blower element is rotated by the gear wheel 71 and co-operation between the screw thread 68 and nut 14 causes the blower element to be projected. During the greater part of the forward movement, the cleaning pressure fluid is excluded from the pressure fluid chamber 5, but when the blower element has been projected to an operative position the cam 26 becomes effective over the blowing angle to effect movement of the valve lid 16 to the open position so that cleaning fluid is projected from the nozzle 3. The arrangement is such that the recess or gap between the inclines 60 and 61 of Figure 3 or 95 and 96 of Figures 4 or 5 first comes below the tappet roller 33, after which rotation of the cam operates the tappet 27 to open the relay valve 8.

When the relay valve 8 opens, pressure fluid, which has leaked from the valve chamber 10 between the piston 7 and cylinder 6 or/and through a small port, not shown, into the space between the piston and cover plate 9, is vented through the tube 47, with the result that the pressure in valve chamber 10 rapidly forces the piston 7 and valve lid 16 to the open position.

When, under the control of cam 26 the relay valve 8 recloses, the leakage of pressure fluid causes the pressure in the space between the piston and cover plate to rise until the spring 11, assisted by gravity, becomes effective in returning the piston and valve lid to the closed position.

Rotation of the shaft 18 in the reverse direction causes movement of the blower element to the retracted position.

In the cleaner described above the blower element may be removed and the valves or piston may be attended to without removing the pressure part or disconnecting the pressure fluid connection thereto. Thus after removing the gland nuts 97 and unclamping the brackets 31 and 75 the blower element may be withdrawn together with the bracket 75 and housings 79 and 91; after disconnecting the tube 47 and removing the cover plate clamping nuts 11, the cover plate 9 may be lifted to give access to piston 7, valve lid 16 and valve seat 14; whilst after removal of the bracket 31, the relay valve may be removed from recess 29 upon unscrewing ferrule 36.

Moreover, the cam 26 may readily be replaced without dismantling the cleaner, since the screw 51 is accessible between the limbs 76 of bracket 75 and the tappet 27 is also accessible. As a result the angle through which blowing takes place may be quickly and easily changed. If desired the direction in which blowing occurs may be

changed by varying the angular position of the nozzle 3 relatively to the tube 1.

In addition the pressure part is of neat and simple construction and suitable for use at high pressures and the screw thread on the blower element is remote from the pressure part and therefore remains relatively cool when steam is used as the cleaning medium.

Having now particularly described and ascertained the nature of our said invention and in what manner the same is to be performed, we declare that what we claim is:

1. In a fluid heater cleaner comprising a movable blower tube adapted to be projected from a retracted position and after operation to be withdrawn to that position, the combination of a casing for the blower element having a fluid inlet through the wall thereof, a valve guarding said inlet and having its housing forming a part of said casing, and a relay valve positioned in said housing for the control of said valve and having a tappet extending through said casing for actuation by said blower tube, said valve being located sufficiently close to the opening occupied by the blower element and to that end of the opening from which the blower element is withdrawn that leakage of fluid past the valve may be observed in said opening and a tool may be inserted through the opening to manipulate said valve on its seat in an effort to dislodge foreign matter.

2. In a fluid heater cleaner comprising a movable blower tube adapted to be projected from a retracted position and after operation to be withdrawn to that position, the combination of a casing for the blower element having a fluid inlet through the wall thereof opening into a fluid chamber, a valve guarding said inlet and having its housing forming a part of said casing, said valve being spring pressed toward its seat in the base of said chamber and having its axis normal to the blower element guarding the outlet from said chamber, a relay valve positioned in said casing for the control of said valve and having its axis normal to the axis of said valve, and a tappet for said relay valve projecting through said casing for actuation by said blower tube, said valve being located sufficiently close to the opening occupied by the blower element and to that end of the opening from which the blower element is withdrawn that leakage of fluid past the valve may be observed in said opening and a tool may be inserted through the opening to manipulate said valve on its seat in an effort to dislodge foreign matter, said relay valve and said tappet each being independently removable.

ROY JAMES GLINN.
PERCY GILBERT HANDOLL.
